UNITED STATES PATENT OFFICE.

MEYER GAFFIN, OF DETROIT, MICHIGAN.

DESIGN FOR A FINGER-RING.

52,788.

Specification for Design.

Patented Dec. 24, 1918.

Application filed July 18, 1918. Serial No. 245,581. Term of patent 14 years.

To all whom it may concern:

Be it known that I, MEYER GAFFIN, a citizen of the United States, residing at Detroit, in the county of Wayne and State of Michigan, have invented a new, original, and ornamental Design for Finger-Rings, of which the following is a specification, reference being had to the accompanying drawing, forming part thereof.

Figure 1 of the drawing is a front elevation, Fig. 2 is a side elevation and Fig. 3 is

a plan of a finger ring showing my new design.

I claim:

The ornamental design for a finger ring consisting of a substantially square table whose edges are beveled, two diagonally opposite corners of the table merging into parallel ornamented cylinders which are substantially continuations of the curved remaining part of the ring.

MEYER GAFFIN.
